DESIGN FOR A TEA-TRAY.

Design No. 12,704, dated January 24, 1882.

UNITED STATES PATENT OFFICE.

WALTER M. CONGER, OF NEWARK, NEW JERSEY.

DESIGN FOR A TEA-TRAY.

SPECIFICATION forming part of Design No. 12,704, dated January 24, 1882.

Application filed June 18, 1881. Term of patent 14 years.

To all whom it may concern:

Be it known that I, WALTER M. CONGER, a citizen of the United States, residing in the city of Newark, county of Essex and State of New Jersey, have invented a new and useful Improvement in Designs for Tea-Trays and Waiters, fully described and represented in the following specification and the accompanying photograph, forming a part of the same.

10 The fac-simile of my design is shown in the annexed photograph, which is taken from an elliptical tray having a flange turned upwardly and outwardly all around its edge; but it is also applicable to round or square trays.

15 The design is shown in the fac-simile in black lines upon a white ground to secure a good photograph, and shows a band of white upon the bottom of the tray adjacent to the border and separated therefrom by a black line. The band is ornamented by a row of dots and dashes arranged alternately along the middle of its width. The flange is shown divided into eleven large spaces by radial or nearly radial lines, the spaces also being separated by nearly square portions of the flange divided into four square parts by central cross-lines. Each of the large spaces is shown divided longitudinally into three parts by two longitudinal lines, and each part is decorated by a flowing line along the middle. Each of the

20 four small squares interposed between the large spaces is ornamented by a group of seven dots in the center.

25 The spaces and squares may cover the entire

width of the flange, or have a border of color 35 outside of them, as shown in the fac-simile.

As it is the form and not the color of the design that is claimed, it is obvious that the same may be produced in any harmonious colors, and that the boundary-lines of the several spaces 40 may be dispensed with when defined by contrasting colors.

The three parallel bands into which each of the large spaces upon the flange is divided may be formed by contrasting colors, and the 45 decoration upon the bands be omitted or varied at pleasure, as the combination of the three bands with the intervening group of four squares constitutes the essential feature of my design. The same may therefore be used upon 50 the flange of a tray with or without the band of color upon the bottom of the tray, and the decoration of the bottom may be varied in any manner without affecting my design, which I claim as follows:

55 The design, substantially as shown and described, for the flange of a tea-tray, consisting of spaces divided in three parallel bands in the manner described, and alternated with groups of four squares in the manner herein set forth.

In testimony whereof I have hereunto set my hand in the presence of two subscribing witnesses:

WALTER M. CONGER.
